[57] ABSTRACT

A pneumatically actuated needle bar mechanism for use in a two-needle sewing machine of the vertical hook lockstitch type is disclosed. The pneumatically actuated needle bar mechanism selectively controls the position of either or both needles and positively locks either or both needles in either the sewing (engaged) position or the non-sewing (disengaged) position. The mechanism is controlled by pedal operated remote pneumatic valves.

TWO-NEEDLE PNEUMATIC DISENGAGING MECHANISM

SUBJECT MATTER OF THE INVENTION

The present invention relates to an improved mechanism for selectively disengaging either or both needles of a two-needle industrial sewing machine.

BACKGROUND OF THE INVENTION

Sewing machines designed for industrial operations frequently include two needles to enable the operator to sew two parallel seams in a single operation. Two-needle machines of the vertical hook lockstitch type as shown, for example, in the Quist U.S. Pat. No. 2,329,484 and the Attwood et al. U.S. Pat. No. 2,765,759 are well adapted for this purpose. When using such a machine for sewing parallel seams it is desirable that either or both of the needles be capable of being raised to a nonoperating or disengaged position to enable the operator to turn left or right seam corners or to avoid an impenetrable portion of the work such as a wire stay or slide fastener.

The art has developed various mechanisms for raising or disengaging the needles of a two-needle sewing machine. Thus, in Basso U.S. Pat. No. 1,899,303 there is provided a single needle supporting bar fitted with a head having separate slide ways for each of the two needle holders. The needle holders are provided with spring-loaded detents to lock the holders in either the engaged or disengaged position. Similar manually operated needle positioning devices are shown in Kufall U.S. Pat. No. 2,495,586, Weigert U.S. Pat. No. 3,763,805 and Shuffield U.S. Pat. No. 3,763,806. While each of the above patents provides a mechanism whereby either or both needles of a two-needle machine can be disengaged, each of these mechanisms requires the operator manually to move a lever or detent mounted directly on the needle holder. This is necessarily a time consuming operation which decreases the productivity of the operator.

Another approach to the problem is shown in the Bono U.S. Pat. No. 3,077,846 and the Kucera U.S. Pat. No. 3,545,390. In these patents two separate needle bars are provided together with a mechanical disengaging means by which either needle bar alone may be disengaged. While the operating levers for these mechanisms have been removed from the needle holder, it is still necessary for the operator manually to move a lever to control the device. These mechanisms are both more complex than those shown in the Basso and Kufall patents and introduce two additional disadvantages into the machine. First, the use of two separate needle bars, in the context of those machines, places a limitation on the proximity of the needles, and, hence, limits the minimum spacing of the parallel seams to be sewn. Second, the mechanism is not capable of disengaging both needles simultaneously. These specific disadvantages have been overcome in the mechanisms of the Benink et al. U.S. Pat. No. 2,868,152 and the Berg et al. U.S. Pat. No. 3,266,449 by the use of a split needle bar which permits closer spacing of the needles and separate mechanically operated disengaging means for each needle bar. However, these mechanical mechanisms must still be manually operated.

SUMMARY OF THE INVENTION

It is an object of the present invention to provide an

improved mechanism to selectively control the position of either or both needles of a two-needle sewing machine. While the present invention will be described in connection with a vertical hook lockstitch sewing machine, it may also be utilized on other types of two-needle sewing machines. Another object of the invention is to provide a positively operating, remotely controlled needle engaging mechanism. A further object of the invention is to provide a pneumatically actuated mechanism which is capable of rapid response to a remote signal and functions to lock the needle in either an engaged or disengaged position. These and other objects of the invention are accomplished by providing a two-needle mechanism for a sewing machine in which a double acting pneumatic cylinder is positioned as an axial extension of each slideable needle bar. Each needle bar actuating cylinder communicates through pneumatic ducts with remotely positioned four-way valves which are actuated by treadles or other means to either of two extreme positions. Actuation of the treadle controls the four-way valve to direct pneumatic pressure into one side of the double acting pneumatic cylinder so as to drive a piston connected to the needle bar into a locked position constituting either an operating (i.e., engaged) position or a nonoperating (i.e., disengaged) position.

BRIEF DESCRIPTION OF THE DRAWINGS

30 The above and other objects of the invention will be more clearly understood when considered in connection with the detailed description and the accompanying drawings in which

35 FIG. 1 is a front elevational view, partly in section, of a two-needle sewing machine incorporating the pneumatic needle disengaging mechanism according to the present invention.

40 FIG. 2 is an elevation view of the left end of the sewing machine as viewed in FIG. 1 with the head cover removed and part of the spacer cut away.

45 FIG. 3 is an enlarged vertical section of the needle bar assembly taken along line 3-3 of FIG. 2.

FIGS. 4A and 4B are, respectively, rear and left side views of the detent bar of the needle bar assembly.

50 FIG. 5 is an exploded view of the parts associated with the right needle bar shown in FIG. 3.

FIGS. 6A and 6B are, respectively, rear and right side views of the retractable needle holder associated with the right needle bar shown in FIG. 3.

55 FIG. 7 is a fragmentary cross-sectional view of the pneumatic system including the double acting pneumatic cylinders for the left and right needle bars, the left and right two-position four-way valves and the air supply and showing the left needle in the retracted or disengaged position while the right needle is in the un-retracted or engaged position.

60 FIG. 8A is a plan view of the left pedal assembly, partly in section, and showing the pedal in a position to retract the left needle.

FIG. 8B is a sectional view of the left pedal assembly taken along the line 8B-8B of FIG. 8A.

65 FIG. 9A is a plan view of the right pedal assembly, partly in section, and showing the pedal in a position to engage the right needle.

FIG. 9B is a sectional view of the right pedal assembly taken along the line 9B-9B of FIG. 9A.

DETAILED DESCRIPTION OF THE PREFERRED EMBODIMENT OF THE INVENTION

Referring first to FIGS. 1 and 2, the sewing machine main frame in which the present invention may be incorporated is indicated generally at 10 and comprises a work supporting base portion 12, a vertical standard 14 and an overhanging arm 16 with a needle head 18 at its free end. A rotatable shaft 20 extending longitudinally within the overhanging arm 16 and suitably journaled therein extends through the right wall of the vertical standard 14 and carries on its right end (as viewed in FIG. 1) a combination hand wheel and pulley 22 and an electromechanical synchronization unit 24. A belt (not shown) from an electrodrive (not shown) drives the pulley 22 and the rotatable shaft 20. The electromechanical synchronization unit 24 supplies electrical signals to the electrodrive to cause the machine to stop with the needle bars in the "up" or "down" position as may be desired by the operator. The synchronization unit may also control the trimming of the thread at the beginning or at the end of a garment stitching operation. The synchronization unit 24 here contemplated may, for example, be a Quick Model No. 800-ST-362 unit or an Amco Model No. 800-XT-362 unit.

The rotatable shaft 20 extends from the pulley 22 into the needle head 18 and is there affixed to a balanced crank member 26 having positioned therein an eccentric pin 28. An intermediate link 30 is rotatably mounted at one end on the eccentric pin 28 and at the other end on pin 32 of collar 34 which, in turn, is secured to the right needle bar 36. Rotation of the shaft 20 causes the needle bar 36 to reciprocate in a generally vertical and axial direction within an oscillatable frame 38 pivoted at its upper end on pin 40. As set forth below, means are provided to rock the frame 38 in the direction of the feed, i.e., in the line of stitch formation, to impart a needle feed action to the work. This rocking motion is derived from a pin 42 attached to the frame 38 and providing a pivotal attachment for one end of a rocker line 44, the other end of which is pivotally connected with arm 46 which extends downwardly and outwardly from collar 48 secured to a hollow rock shaft 50.

The lower end of the right needle bar 36 is fastened to a needle bar clamp 52 by a dog screw 54. In similar manner the lower end of the left needle bar 56 is fastened to the needle bar clamp 52 by a dog screw 58 (see FIG. 3). As the left and right needle bars 56 and 36, respectively, are thus clamped together, both will reciprocate when the right needle bar 36 is driven with a reciprocating motion as set forth above.

As shown most clearly in FIGS. 3 and 5, both needle bars 36 and 56 are hollow and both contain identical parts. For this reason, the right needle bar assembly only will be described in detail and the corresponding parts of the left needle bar assembly identified by primed numbers. A similar practice will be followed with respect to the left and right pedal assemblies (FIGS. 8 and 9) and the pneumatic control system (FIG. 7). The needle bar mechanism used in the present invention is also shown in my copending application Ser. No. 402,876 entitled "Sewing Apparatus" filed Oct. 2, 1973.

Referring now principally to FIGS. 3 and 5, air hose 60 communicates with the top of the needle bar 36 by means of a hollow threaded nut 62 which is threaded

5 into the needle bar and an air collar 64. Air hose 60 communicates with the air collar 64 through a radial hole 66 formed in the collar 64 and the fitting 68 soldered into the collar 64. Air collar 64 is fastened to the top of the needle bar 36 by a screw 70 provided with an axial bore 72 which communicates with a radial bore 74. Screw 70 is threaded into the hollow nut 62 with its radial bore 74 aligned with the radial hole 66 of the air collar 64 to provide an air passage communicating between the air hose 60 and the interior portion of the needle bar 36. In a similar manner, air hose 76 (FIG. 7) is connected to the needle bar 36 by an air inlet collar 78 through an aligned radial hole formed in the collar and a radial hole 80 formed in the needle bar 36. Air hose 76 communicates with the needle bar at a point just above the dividing seal portion 82 of the needle bar.

20 An air piston 84 is slidably mounted within the needle bar 36 between the air intake points corresponding to air hoses 60 and 76 and is fastened to piston rod 86 by a nut 88. A cup seal 90 is positioned around the piston rod 86 and within the needle bar 36 so as to form a lower pressure chamber within the needle bar 36 and bounded at the ends by piston 84 and cup seal 90. Thus 25 the air piston 84 forms the movable element in a double acting pneumatic cylinder and will be driven downwardly when air is admitted into the needle bar through air hose 60. Similarly, piston 84 will be driven upwardly when air is admitted into the needle bar through air hose 76. The lower end of the piston rod, after passing through the dividing seal portion 82, is welded to cam member 92 (FIG. 5). Cam member 92 has formed on its lower end angularly disposed upper and lower camming surfaces 94 and 96 adapted to selectively engage 30 movable locking balls 98, 100. Locking balls 98, 100 are slidably mounted within a retractable needle holder 102 (see FIGS. 6A and 6B) which, in turn, is slidable within a vertical slot 104 formed in the needle bar 36. 35 A detent bar 106 (see FIGS. 4A and 4B) is secured to the lower end of needle bar 36 by dog screw 54. Similarly, detent bar 106' is secured to the lower end of needle bar 56 by dog screw 58.

40 As shown in FIGS. 5, 6A and 6B, the retractable needle holder 102 has a cylindrical upper section 108 that has been longitudinally sectioned off to form a flat portion 110 and a plate-like lower section 112. A vertical slot 114 extends from the flat 110 into the cylindrical section 108 and down into the plate-like lower section 112. Two horizontal holes 116, 118 having diameters 45 larger than the width of the vertical slot 114 are bored from the flat 110 into the cylindrical section 108 with the slot 114 bisecting the holes. The upper and lower locking balls 98, 100 are free to move horizontally within the holes 116, 118, respectively, but are restrained by the holes 116, 118 from motion in the vertical direction. In the lower portion of the needle holder 102 a vertically directed hole 120 is formed to receive a needle 122 while a horizontal hole 124 serves as a needle stop. The needle 122 is locked into position by 50 a set screw 126 threaded into the horizontal locking hole 128.

55 The cam member 92 (FIGS. 3 and 5) is formed with flat sides so as to slide within the vertical slot 114 of the retractable needle holder 102. Lower camming surface 96 of the cam member 92 is adapted to contact locking ball 100 and urge said locking ball outwardly from the needle holder 102 along hole 118 when the piston 84

is driven downwardly within the needle bar 36. Similarly, the upper camming surface 94 is adapted to contact the upper locking ball 98 and urge said locking ball outwardly from the needle holder 102 along hole 116 when the piston 84 is driven upwardly within the needle bar 36.

The detent bar 106 (FIGS. 4A, 4B and 5) includes as its upper section the dividing seal portion 82. The central section 130 of the detent bar is sectioned longitudinally from a cylinder to form a flat 132 which mates with the flat 110 of the retractable needle holder 102. Two shallow holes 134, 136 are formed in the flat 132. The shallow holes 134 and 136 are smaller in diameter than the locking balls 98, 100 so as to allow a portion of said balls to protrude from the retractable needle holder 102 into the detent bar 106 when aligned respectively with the upper or lower horizontal holes 116, 118. The lower section 138 of the detent bar 106 is cylindrical in shape and has formed therein a slot 140 to receive the plate-like section 112 of the retractable needle holder 102. Two holes 142, 144 are formed in the cylindrical section 138 of the detent bar 106. The upper hole 142 is aligned to receive the top of the dog screw 54 and thereby secure the detent bar 106 to the needle bar 36 while the lower hole 144 is provided for access to the needle set screw 126. Horizontal circular groove 146 is aligned with the needle stop hole 124 in the retractable needle holder 102 when the needle holder is in the operating or unretracted position to permit observation of the position of the needle 122 within the needle holder.

A small horizontal hole 148 is formed in the lower portion of the needle bar clamp 52 perpendicular to the plane of the needle bars 36 and 56 and midway between the axes of the needle bars to receive a roll pin 150. The roll pin 150 is adapted to abut against and support the adjacent needle holder 102 or 102' so as to prevent the lateral deflection of either needle holder 102 or 102' when the other needle holder is in the retracted position. Thus, as shown in FIG. 3, the roll pin 150 prevents a lateral deflection of the needle holder 102 in a leftward direction when needle holder 102' is in its retracted position. Horizontal holes 152, 152' in the needle bar claim 52 are formed in alignment with circular groove 146 of the detent bar 106 to permit observation that the needles 122 are properly seated while horizontal holes 154, 154' are aligned with holes 144, 144' of the detent bar 106, 106' to provide access to the needle set screws 126, 126'.

FIG. 7 illustrates in diagrammatic form the pneumatic supply and control system for the needle bar actuating mechanism of the present invention. Air from an air supply source 156 enters a tee connector 158 and is divided between two air supply tubes 160, 160'. The air supply tube 160 communicates with the right four-way valve 162. Valve 162 comprises a cylindrical body 164 and an axially disposed spool 166. The valve body contains five air ports including a central air supply port 168 which communicates with the air supply tube 160, two outlet pressure ports 170, 172 which communicate, respectively, with the air hoses 60 and 76 and two exhaust ports 174, 176 positioned outwardly from the outlet pressure ports 170, 172. The spool 166 of the valve 162 comprises a central rod 178 and three piston portions 180 and actuating heads 182, 183 affixed at each end of the central rod 178. As shown in FIG. 7, a spring 184 urges the spool 166 into

a left operating position within the valve body 164 whereby ports 168 and 170 are in communication and ports 172 and 176 are in communication. Under these circumstances, pressurized air from the air supply 156 is directed through the air supply tube 160, through the valve body 164 and air hole 60 into the upper portion of the needle bar 36 whereby the piston 84, the piston rod 86, the cam member 92 and the needle holder 102 are driven downwardly within the needle bar 36. As the cam member 92 moves downwardly, the camming surface 96 urges locking ball 100 outwardly against the flat 132 of the detent bar 106. When the locking ball 100 becomes aligned with the shallow hole 136 in the detent bar 106, the cam surface 96 will urge the ball partially into the shallow hole 136 whereby the needle holder 102 will be locked in the engaged or sewing position.

When the spool 166' has been moved to the right within valve body 164' so as to compress the return spring 184' as shown in FIG. 7, air from the air supply 156 is directed through air supply tube 160', air supply port 168', outlet pressure port 172' and air hose 76' into the left needle bar 56 below the air piston 84'. Air pressure acting on the lower side of the air piston 84' drives the piston upwardly in the needle bar assembly and carries with it piston rod 86', the cam member 92' and the needle holder 102'. As the cam member 92' moves upwardly, the camming surface 94' urges locking ball 98' upwardly and outwardly against the flat 132' of the detent bar 106'. When the locking ball 98' becomes aligned with the shallow hole 134' in the detent bar 106', the cam surface 94' will urge the ball partially into the shallow hole 134' whereby the needle holder 102' will be locked in the disengaged or nonsewing position.

It will be appreciated that when the spool 166 of the right four-way valve is in the left position as shown in FIG. 7 so as to admit air under pressure into the upper portion of the right needle bar 36, the portion of the needle bar 36 below the piston 84 communicates to the atmosphere through air hose 76, pressure port 172 and exhaust port 176. Similarly, when the spool 166' is in the right position as shown in FIG. 7 so as to admit air under pressure into the lower portion of the left needle bar 56, the portion of the needle bar 56 above the piston 84' communicates to the atmosphere through air hole 60', pressure port 170' and exhaust port 174'.

Use of the pneumatic system as shown diagrammatically in FIG. 7 permits both needles of a double needle sewing machine to be moved to either an operating or a nonoperating position by means of remotely located four-way valves. The valves are provided with compression springs 184, 184' arranged normally to cause both needles to be in the operating or sewing position.

In order to provide for maximum efficiency and convenience, the four-way pneumatic control valves 162 and 162' may be incorporated into pedal assemblies or treadles as shown in FIGS. 8A, 8B, 9A and 9B. The pedal assemblies conveniently may be permanently affixed to the sewing machine stand (not shown).

As shown in FIGS. 9A and 9B, the right pedal assembly comprises a box 186 having a bottom portion 188, left and right side portions 190, 192, a front portion 194 and a rear portion 196. A pipe support flange 198 is secured to the bottom portion 188 by two screws 200. Pipe support flange 198 is appropriately formed to engage treadle pipe 202 which forms a portion of the

sewing machine stand (not shown). A flange member 204 is fastened to the rear portion 196 by means of screws 206. The flange member 204 is provided with appropriate slots 208 for affixing the flange member to the sewing machine stand.

The four-way valve 162 is positioned within the pedal box 186 by means of a pair of connectors 210 which are threaded on each end of the four-way valve 162 and fastened to the bottom portion 188 of the pedal box 186 by screws 212. Air hoses 60, 76 and 160 are secured to the bottom portion 188 by a claim 214 and lock screw 216 and exit from the pedal box 186 through a grommet 218 mounted in the rear portion 196. Pedal 220 pivots on a shaft 222 mounted in the side portions 190, 192. The pedal 220 and shaft 222 are held in position by retaining rings 224. A screw 226 is adjustably secured to the right edge of the pedal 220 and locked into position by lock nut 228. The screw 226 is located so that when the pedal is positioned as shown by the solid lines in FIG. 9B, screw 226 will be aligned with the axis of the spool 166 of the four-way valve 162. Screw 226 is then adjusted so that it contacts the adjacent spool actuating head 182 and drives the spool 166 into its left operating position. In similar manner, a screw 230 is adjustably secured to the left edge of the pedal 220 and locked into position by a lock nut 232. Screw 230 is located so that when the pedal 220 is positioned as shown by the broken lines in FIG. 9B, screw 230 will be aligned with the axis of the spool 166 of the four-way valve 162. Screw 230 is then adjusted so that it contacts the adjacent spool actuating head 183 and drives the spool 166 into its right operating position. In FIGS. 8A and 8B the left pedal assembly is shown with the pedal 220 depressed so that the adjustable screw 230 contacts the spool actuator 183' and drives the spool 166' of the four-way valve 162' into the right operating position.

Referring to FIGS. 3, 7, 8A, 8B, 9A and 9B, it will be appreciated that when the pedal 220 or 220' is in the position shown in FIG. 9B, i.e., the pedal is not depressed, the corresponding holder 102 or 102' and the associated needle 122 or 122' will be in the operating or sewing position. However, when the pedal 220 or 220' is in the position shown in FIG. 8B, i.e., the pedal is depressed, the corresponding needle holder 102 or 102' and associated needle 122 or 122' will be in the retracted or nonoperating position.

The mechanism herein provided enables the operator quickly and positively to actuate either or both needles to the desired position without removing the operator's hands from the work. This is particularly advantageous where parallel seaming operations are being performed on garments such as coat lapels or shirt collars or pockets where it is desirable not to have the lines of stitching cross and where either or both right-hand and left-hand corners are involved. When it is necessary for a parallel seam to cross cording, a stay, a wire or a fastener, it may be necessary to retract both needles either simultaneously or sequentially and to reengage the needles either in the same or another sequence.

While the invention has been described in connection with specific illustrative embodiments thereof and in specific uses, it should be understood that it is not limited thereto since obvious modifications thereof will occur to those skilled in the art without parting from the spirit and scope of the invention as set forth in the appended claims.

What is claimed is:

1. In a sewing machine designed to sew stitches in parallel spaced lines, the apparatus comprising a pair of needle bar means each including a needle bar and a needle for forming stitches from a respective thread, means actuated pneumatically within each of said needle bars and connected with said needle and adapted to move said needle axially with respect to said needle bar between a first engaged position and a second disengaged position, a source of pressurized air, and a pair of valve means in communication with said source of pressurized air and said pneumatically actuated means, each of said valve means operable between first and second positions to direct air under pressure into said pneumatically actuated means, said valve means in its said first position adapted to direct air under pressure into said pneumatically actuated means so as to drive said needle into its first engaged position, said valve means in its second position adapted to direct air under pressure into said pneumatically actuated means so as to drive said needle into its second disengaged position.

2. The apparatus of claim 1 including: a means associated with each of said valve means to position said valve means in either of said first or second positions.

3. The apparatus of claim 1 including: a locking means within each of said needle bar means adapted to retain said needle in one of said first or second positions.

4. In a sewing machine designed to sew stitches in parallel spaced lines, the apparatus comprising a pair of needle bar means each including a needle bar and a needle for forming stitches from a respective thread, means actuated pneumatically within each of said needle bars including movable piston means connected with said needle and adapted to move said needle axially with respect to said needle bar between a first engaged position and a second disengaged position, camming means connected to said piston means for reciprocating motion therewith in a first axial direction, upper and lower locking means driveably cooperating with said camming means, needle holder means driveably connected to said camming means through said locking means for reciprocating motion in said first direction, said locking means arranged for sliding motion relative to said needle holder means in a second direction transverse to said first direction under the influence of said camming means, detent means fixed to said needle bar means including upper and lower locking recesses adapted to engage, respectively, said upper and lower locking means, said lower recess defining a first engaged position of said needle and said upper recess defining a second disengaged position of said needle, a source of pressurized air, and a pair of valve means in communication with said source of pressurized air and said pneumatically actuated means, each of said valve means operable between first and second positions to direct air under pressure into said pneumatically actuated means, said valve means in its said first position adapted to direct air under pressure into said pneumatically actuated means so as to drive said needle into its first engaged position wherein said lower locking means is engaged with said lower recess of said detent means, said valve means in its second position adapted to direct air under pressure into said pneumatically actuated means so as to drive said needle into its second disengaged position wherein said upper locking

means is engaged with said upper recess of said detent means.

5. The apparatus of claim 4 including: means associated with each of said valve means to position said valve means in either of said first or second positions. 5

6. The apparatus of claim 4 including: oscillatable pedal means drivingly engaged with each of said valve means to position said valve means in either of said first or second positions.
